US0D1084841S

(12) **United States Design Patent** (10) **Patent No.:** **US D1,084,841 S**
(45) **Date of Patent:** **** Jul. 22, 2025**

(54) **CAP**

(71) Applicant: **UNIK WORLD INDUSTRIAL CO., LTD.**, Tainan (TW)

(72) Inventors: **Wen San Chou**, Tainan (TW); **Cheng Hsien Chou**, Tainan (TW)

(73) Assignee: **UNIK WORLD INDUSTRIAL CO., LTD.**, Tainan (TW)

(**) Term: **15 Years**

(21) Appl. No.: **29/917,528**

(22) Filed: **Nov. 20, 2023**

(30) **Foreign Application Priority Data**

Oct. 30, 2023 (TW) 112305568

(51) **LOC (15) Cl.** **08-08**

(52) **U.S. Cl.**

(57) **CLAIM**

The ornamental design for a cap as shown and described.

DESCRIPTION

FIG. 1 is a perspective view of a cap showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a cross-sectional view taken in the direction of line 9-9 in FIG. 3; and,

FIG. 10 is a cross-sectional view taken in the direction of line 10-10 in FIG. 7.

The broken lines in FIG. 3 and FIG. 7 illustrate the cross-sectional cut plane of the cap that forms no part of the claimed design.

1 Claim, 10 Drawing Sheets
